UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

1,417,646.

Specification of Letters Patent. Patented May 30, 1922.

Application filed April 21, 1921. Serial No. 463,187.

To all whom it may concern:

Be it known that I, FRANKLIN R. WHITE, a citizen of the United States, and a resident of Waterbury, in the county of New Haven 5 and State of Connecticut, have made and invented certain new and useful Improvements in Buttons, of which the following is a specification.

My invention relates to buttons and particularly to that type thereof comprising a head and fastener, the latter being adapted to pierce the cloth or other material and securely attach the head of the button thereto, the entire operation being carried out by 10 the use of an automatic button attaching machine. In this type of button it is customary to provide an anvil which is adapted to take up the thrust and stresses incident to the heading of the prong of the fastener 15 within the body portion of the button and considerable trouble and complaint have heretofore been experienced due to the rattling of the anvil within the body of the button after the button has been secured to a 20 garment.

It is accordingly an object of my invention to provide a button wherein the anvil is securely held against movement and thus the button insured against rattling.

30 A further object is to accomplish the aforementioned ends in a novel and simple manner and thereby provide a button which may be easily and economically manufactured and the various parts easily held to the desired 35 limits as to size, so as to accomplish the afore-mentioned ends, and the button may therefore be produced under ordinary commercial conditions such as necessarily exist where quantity production is desired.

40 With the foregoing and other objects in view, which will appear as the description proceeds, my invention resides in the novel button described and in the combination and arrangement of parts and in the details of 45 construction hereinafter described and claimed, the preferred embodiment of my invention being disclosed in the accompanying drawing, wherein:

Figure 1 is a view in longitudinal vertical section of a button having the characteristic features of my invention, the parts being illustrated prior to the securement of the button to cloth or other material;

Figure 2 is a similar view of the button after the attachment of the button; 55

Figure 3 is a view in top plan and partially in section of my improved button;

Figure 4 is a view in longitudinal vertical section of a slightly modified form;

Figure 5 is a view in vertical longitudinal section of a somewhat further modification of my invention, the button being formed with a square anvil;

Figure 6 is a top plan view of a modified button having portions of the cap removed 65 so as to disclose the square anvil;

Figure 7 is a view in vertical longitudinal section of a button having a square anvil, the latter being provided with a thickened center; 70

Figure 8 is a detail view in perspective of the latter-mentioned form of anvil.

Figure 9 is a modified form of button wherein the usual anchor is omitted and the tack headed directly against the anvil; 75

Figure 10 is a similar view showing the button attached;

Figure 11 is a view in longitudinal vertical section of a button having a reinforced base and a shell anchor; and 80

Figure 12 is a view in vertical longitudinal section of my improved button having a perforated base with the edges rolled over so as to engage the shell-like anchor.

Referring to the several views, wherein 85 similar reference numerals designate corresponding parts throughout, my improved button as disclosed in Figures 1 and 2 is formed with the head A and the fastener B, the latter being adapted to pierce the cloth 90 or other material C and securely anchor the head of the button thereto. The head of the button is formed with the body portion 10, hub 11 and base 12, the latter being imperforate in the buttons shown in 95 Figures 1 to 5 and perforated in the buttons shown in Figures 7 to 12, as my invention is applicable to buttons with either perforate or imperforate bases. The hub 11 is slightly tapering and receives the 100 anchor member 13 therein, the same having a central opening 14 in its base in alignment with the central indentation or recess 15 formed in the imperforate base, so that the prong 16 of the fastener after being 105 driven through the material C is guided

through the opening 14 in the anchor and will be headed and permanently secured therein, as illustrated in Figure 2.

The button is provided with the customary cap or top 17 and with the anvil 18 held in place by the cap. Buttons of this type, and particularly where the head of the button is of considerable diameter, have heretofore been objectionable due to the rattling of the anvil 18 within the head of the button. In order to eliminate this and to hold the anchor rigidly in place, I have provided the body portion 10 of the button with the upstanding ring or ledge 19 which is adapted to receive the anvil 18 thereon and in connection with the cap 17 hold the anvil in place. The dimensions or size of the ring or ledge 19 may be easily held to the required limits even though the button be manufactured under quantity production conditions, this being particularly true due to the close proximity of the top of the ledge 19 and the upper rim of the body portion 10, which are the two parts which determine or control the distance between the lower surface of the cap 17 and the upper surface of the ledge 19. While the ledge has been described and illustrated as being annular or continuous in outline, it will be readily appreciated that it may partake of the nature of local indentations; that is to say, the ledge need not be continuous in order to hold the anvil against rattling.

A further feature of my invention resides in the utilization of the compressing strains incident to the heading of the fastener prong in the button to cause the body portion to take a permanent set, particularly at the portion designated at 20 in Figure 2, and this slight permanent set or distortion results in the anvil being more firmly held between the ledge 19 and the cap 17 of the button and thus positively preventing any rattling of the anvil.

The somewhat modified form of button illustrated in Figure 4 is similar to the foregoing, with the exception that the anvil 21 is of restricted diameter and instead of extending across the upstanding annular ledge 22 is confined between the walls thereof and thus held against rattling or displacement in any direction. This type of button may also be manufactured in large quantities and with little difficulty in holding the parts to the desired dimensional limits, so that each and every button after being secured in place will not only possess all the advantages of this type of button as heretofore experienced but in addition will be free from the very objectionable feature of rattling, which impresses one with the idea that the button is not properly secured in place or that the button is in other ways defective.

The somewhat further modification illustrated in Figures 5 and 6 is modified only to the extent of providing a non-circular or polygonal anvil 23, the anvil in this instance being illustrated as being square, so that the corners 24 extend approximately to the periphery of the body portion of the button and in conjunction with the upstanding annular ledge 25 rigidly hold the anvil in place. 75

In some instances I have found that the blanking of the anvil may leave a bur and in order to prevent the same from marring the top of the button, I have provided a modified form of anvil as illustrated in Figure 8, polygonal in outline, the present type being shown as square and provided with a thickened center 26, the thickened center 26 holding the protruding and thinner edges 27 away from the top or cap of the button, as clearly illustrated in Figure 7. This anvil is also used in conjunction with a button having an annular ledge 28 or in fact may be used with a button wherein the ledge is omitted, as the projecting corners of the polygonal anvil successfully hold the button against rattling. 80 85 90

In order to illustrate that the above-mentioned features may be incorporated in various styles of buttons as heretofore formed, I have included in the drawings Figures 9, 10, 11 and 12, wherein the buttons are provided in Figures 9 and 10 with a perforated base 29, in connection with which operates a tack 30. The remaining portions of the button are formed as previously outlined, the anvil 31 resting upon and being held against rattling by the upstanding ledge 32. In this particular button the tack 30 is headed so as to rest directly upon and contact with the base 29, thus rendering unnecessary the use of an anchor. In Figure 11 the perforated base 33 is reinforced as at 34 and is provided with the cup-shape anchor 35, the latter bearing against the anvil 36. The button disclosed in Figure 12 has the shell anchor 38 held in place by rolling or protruding the edges of the base, as at 37. It will thus be seen that my improved button formation may be used in connection with various types of buttons and in each instance will provide for the successful heading of the tack and the prevention of the rattling of the anvil after the button has been fastened in place. 100 105 110 115 120

With the various parts constructed as above outlined, the anvil is not only held against rattling but is also held in contact with the top of the anchor 13 so that the forces brought to bear upon the various parts of the button during the attachment of the fastener and the heading of the prong will be properly taken up and transmitted by the various parts, thus preventing the undue distortion or destruction of the button, although 130

allowing for its slight bending, as illustrated at 20 in Figure 2.

Having thus described and explained my invention, I claim and desire to secure by 5 Letters Patent:

1. A button comprising a body portion having an upstanding ledge, a cap for said body portion, an anvil within said body portion and held in place between said cap and said ledge, said anvil adapted to receive and take up the strains incident to the heading of a fastener within said button. 10

2. A button comprising a body portion having an upstanding ledge, a cap for said body portion, an anvil within said body portion held in place against rattling by said upstanding ledge and cap, a body portion provided with a hub adapted to receive a fastener therein, the said anvil providing 20 for the heading of said fastener.

3. A button of the class described comprising a body portion having an upstanding ledge, a cap for said body portion, an anvil within said body portion and held in place 25 against rattling by said ledge and cap, said body portion including a hub, an anchor member located within said hub and bearing against said anvil and adapted to receive and head a fastener therein.

30 4. A button comprising a body portion, an upstanding member adjacent the upper rim of the body portion, a cap for said body portion, and an anvil within said body portion and firmly held in place between said cap and 35 said upstanding member, said anvil adapted to receive the strains incident to the heading of a fastener within said button.

5. A button comprising a body portion having an upstanding annular ledge, a cap for said body portion, and a polygonal anvil located within said body portion and held 40 against shifting by said annular ledge and said cap.

45 6. A button comprising a body portion, a hub and a cap, a polygonal anvil located

within said body portion and provided with a thickened center and adapted to hold the projecting corners of said anvil out of contact with said cap, said polygonal anvil held 50 against shifting and rattling.

7. A button of the class described comprising a body portion, a cap and a hub, said body portion provided with an upstanding annular ledge, a polygonal anvil provided with a thickened center held in position by the projecting corners and by said upstanding ledge. 55

8. An anvil for buttons of the class described polygonal in outline and provided with a thickened center adapted to maintain 60 the edges of the anvil out of contact with a button cap.

9. An anvil for buttons provided with a thickened center, the said thickened center adapted to contact with portions of the button and be held against movement and to maintain the edges of the anvil out of contact 65 with the button cap.

10. A button comprising a body portion, a hub, and a cap, an anvil located within said body portion and provided with a thickened center, said thickened center contacting with the body portion and cap and held against movement thereby, said thickened center holding the edges of the anvil out of contact 70 with the cap. 75

11. A button comprising a body portion, a hub and a cap, said body portion provided with an upstanding ledge, an anvil with a thickened center, said thickened center held 80 in position between the said ledge and the cap, and with the edges of the anvil held out of contact with the cap.

Signed at Waterbury, in the county of New Haven and State of Connecticut, this 85 ninth day of April, A. D. 1921.

FRANKLIN R. WHITE.
